UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed September 5, 1924. Serial No. 736,037.

To all whom it may concern:

Be it known that I, NORMAN B. HURD, a citizen of the United States of America, residing at New Britain, Connecticut, have 5 invented a new and useful Lock, of which the following is a specification.

My invention relates to a lock, particularly, though not exclusively, adapted for use on automobile doors and the like.

10 It is an object of the invention to provide a lock of serviceable and rugged construction wherein the locking bolt is moved in one direction by key-controlled means, and which may be moved in the opposite direction by a spring.

Other objects will be apparent as the specification proceeds.

15 In the accompanying drawings, which show for illustrative purposes only, a preferred form of the invention,

Fig. 1 is a front side view of my improved lock applied to a door member;

Fig. 2 is a rear side view of the lock;

Fig. 3 is a rear edge view of the lock, and

20 Fig. 4 is a bottom edge view taken at right angles to Fig. 3.

The lock may be applied to either the door or jamb and, in the illustrative form shown, is secured to the door diagrammatically shown at 5. 6 indicates diagrammatically the usual door jamb. The improved form of lock has a frame or lock casing 7, provided with a front upstanding flange or face member 8. The flange 8 may be provided with 25 apertures as at 9-9 for the reception of screws or the like, for securing the lock frame in place.

The rear end of the frame 7 is enlarged so as to provide a boss 10 which is bored to 30 receive the cylinder 11 of any suitable type of cylinder lock. A cylinder plug 12 fits in the cylinder 11 and the usual pin tumblers are provided in the cylinder and plug. The rear end of the plug has a rollback 13 thereon. The cylinder may be held in place in the boss 10 by any suitable means, such as a screw 14, which passes through the wall of the boss 10 and engages the cylinder for 35 positioning the same.

The front flange 8 is apertured to permit 50 the passage of a locking bolt 15 which, in the form shown, is of substantially cylindrical shape and has a rounded forward end. In the rear of the flange 8 the frame has a lug 16, which is also provided with a passageway for the locking bolt 15, which bolt is thus guided and positioned by means of the passages in the flange 8 and lug 16. The rear end of the locking bolt 15 may be provided with means such as a flange or head 55 17, to be engaged by the rollback 13, so as to permit actuation of the locking bolt by the key-controlled plug 12.

In the present disclosure, the key-controlled plug and rollback serve to move the 60 locking bolt to the locked position, as indicated in Fig. 1. The locking bolt is retracted by a spring, which, in the form shown, is a coil spring 18 surrounding the locking bolt and engaging the rear of the front 65 flange 8, and engaging a suitable abutment, such as a cotter pin 19, on the locking bolt.

It will be plain that when the key is inserted in the lock so as to release the tumblers and the key is then released, the re- 70 tracting spring 18 will withdraw the locking bolt 15 from the keeper 20 on the door jamb. In order to remove the key it will be necessary to rotate the plug so as to position the rollback 13 behind the head 17 as 75 shown in Fig. 2 and the bolt 15 will then be held in the unlocked position. When the bolt is in locked position (Fig. 1) and the key is withdrawn from the cylinder lock plug by a longitudinal movement, the pin 80 tumblers therein will be shifted to hold the plug against rotation and thereby hold the bolt in locked position. When it is desired to retract the bolt the key is inserted into the plug and rotated sufficiently to release 85 the binding strain on the tumblers occasioned by the spring 18, whereupon said tumblers will move to release the plug, thereby permitting it to turn so that the locking bolt will be retracted.

90 While I have described one embodiment of the invention in some detail, I wish it understood that the drawings are but il-

lustrative and that changes may be made within the scope of the invention as defined in the appended claim.

I claim:

- 5 In a lock, a lock frame, a locking bolt mounted for movement thereon, a key operated cylinder lock on said frame, a roll-back on the plug of said cylinder lock and

adapted to project said locking bolt into locking position, a spring for moving said locking bolt in an unlocking direction, and means operated by a longitudinal movement of the lock key to hold the bolt in locking position.

NORMAN B. HURD.
